TABLE FORK

Jose Carlos Mario Bornancini, Porto Alegre, Brazil, assignor to Hercules S.A.-Fabrica de Talheres, Rio Grande do Sul, Brazil, a corporation of Brazil

Filed July 10, 1969, Ser. No. 18,157

Term of patent 14 years

Int. Cl. D7—03

U.S. Cl. D54—12

FIG. 1

FIG. 2

FIG. 3

— FIG. 4

— FIG. 5

In the drawings:

FIG. 1 is a front view of a table fork showing my new design;

FIG. 2 is a side view of the table fork;

FIG. 3 is a back view;

FIG. 4 is a section taken on the line 4—4 of FIG. 1; and

FIG. 5 is a section taken on the line 5—5 of FIG. 1.

The side opposite that shown in FIG. 2 is a mirror image thereof.

I claim:

The ornamental design for a table fork, as shown and described.
